DESIGN FOR A BUCKLE

Jacob I. Schaffer, New York, N. Y.

Application August 5, 1935, Serial No. 57,941

Term of patent 3½ years

To all whom it may concern:

Be it known that I, Jacob I. Schaffer, a citizen of the United States of America, residing in Manhattan, county of New York, and State of New York, have invented a new, original, and ornamental Design for a Buckle, of which the following is a specification, reference being had to the accompanying drawing, forming part thereof, wherein,

Figure 1 is a plan view of a buckle showing my new design.

Figure 2 is an elevational side view of the buckle shown in Figure 1.

I claim:

The ornamental design for a buckle, substantially as shown.

JACOB I. SCHAFFER.
